UNITED STATES PATENT OFFICE.

ROBERT L. COCHRANE, OF CHICAGO, ILLINOIS.

TIE-SPACING DEVICE.

1,163,627.

Specification of Letters Patent.

Patented Dec. 7, 1915.

Application filed October 29, 1914. Serial No. 869,335.

To all whom it may concern:

Be it known that I, ROBERT L. COCHRANE, a citizen of the United States, residing at Chicago, in the county of Cook and State of Illinois, have invented new and useful Improvements in Tie-Spacing Devices, of which the following is a full, clear, concise, and exact description, reference being had to the accompanying drawing, forming a part of this specification.

My invention relates to improvements in tie-spacing devices.

One object of the invention is to provide a device which may be used either for spacing the ties on a bridge or for distributing the thrust of an anti-creeper over two or more ties.

Another object is to provide a tie spacer which may be readily applied or renewed without necessitating lifting the rail from the tie or otherwise disturbing the track.

Further objects will be apparent from the following description.

In the accompanying drawings, I have illustrated a tie spacer which embodies my invention. I do not desire to limit myself, however, to the structural form disclosed as various modifications may be made therein.

Figure 1 is a top plan view of a portion of a railway track on a bridge. Fig. 2 is a side elevation thereof. Fig. 3 is a perspective view on an enlarged scale of the tie spacer. Fig. 4 is a bottom view thereof. Fig. 5 is a top plan view of a short length of railway track showing the tie spacer used in combination with an anti-creeper.

The portion of the bridge floor shown in Figs. 1 and 2 comprises the usual cross-ties supported on stringers 2 and having guard rails 3 arranged at the outer ends thereof. Rails 4 are supported on the cross-ties in the usual manner. In order to maintain the cross-ties in proper spaced relation, I provide tie spacing devices 5 arranged at both ends of the ties and preferably between the rail and the guard rail. The tie spacers are thus independent of and do not interfere with the use of the ordinary tie-plates 6, where the latter are desirable. The tie-spacer in the form illustrated, is a casting of malleable iron, cast iron or other suitable material, and is provided with a pair of downwardly extending flanges 7 near the opposite ends thereof. Said flanges are quite deep as compared to the width of the

tie-spacers so as to afford ample surface to engage the side of a tie even where the tie is somewhat irregular. Bridge ties are usually quite regular, however, being sawed to a uniform cross section and accordingly where used with such ties, the vertical depth need not necessarily be as great as under other conditions of use, since the maximum vertical bearing surface provided by said flanges, is available. The said flanges are reinforced by a compression member 8, integral therewith and preferably centrally located, thereby adapting the tie-spacer to transmit an enormous thrust from one tie to the other. In order to avoid an excessively heavy casting, the compression member is preferably of reduced width having the form of what may be called a web, although by this term I do not necessarily limit myself to a thin member. The tie-spacers are permanently held in place preferably by nails or spikes 9 driven through suitable openings 10 in opposite ends thereof, or by suitable equivalent means. Said tie-spacers need not necessarily be arranged outside of the rails.

By using tie-spacers such as described herein, "dapping" of the guard rails, that is, notching them out on the under side, may be dispensed with, the notched out portions of the guard rail fit over the ties thereby maintaining the latter in proper spaced relation. The elimination of the dapping operation results in increased economy, not only in the time and labor saved, but because of the fact that a guard rail of smaller cross section may be used. In fact, by using steel rails as guard rails, and locating the latter between the regular rails, the wooden guard rails may be dispensed with entirely, although the fact that their use has become customary, may make it advisable to retain them for the sake of appearance. On ordinary railway tracks, the rail joints are prevented from advancing or creeping over the ties by the spikes which pass through notches in the splice bars. In tracks, as customarily laid on bridges, the rail joints are not thus secured to the ties as creeping of the rails would result in bunching up the ties unless "dapping" is made use of. By using my improved tie-spacer, however, the rail joints on bridges may be secured to the ties in the same way that they are secured in ordinary ballasted track. This is due to the fact that all of the ties being rigidly

spaced and interconnected, the creeping thrust may be distributed throughout all of said ties.

A further important use for the device is in conjunction with an anti-creeper, as shown in Fig. 5. The rail 11 is supported on cross-ties 12 which latter may be more or less irregular in cross section, or at least devoid of square corners. The anti-creeper 13 is applied to the rail base adjacent to one of the ties in the customary manner. The anti-creeper shown is intended to be typical of any standard anti-creeper. The tie-spacers are applied to the ties preferably outside of the rails, although not necessarily so, one or two tie-spacers being ordinarily sufficient. The anti-creeper transmits the creeping thrust to the tie which it engages, said tie transmitting a part of said thrust to the adjacent tie or ties so that the thrust is resisted by more than one tie. Even if the ties are somewhat irregular, the depending flange 7 is sufficiently deep to engage some part of the vertical face thereof to insure a firm seat.

By using my improved tie-spacer in conjunction with an anti-creeper, the number of anti-creepers employed may be much reduced thereby effecting a substantial economy, as the cost of the tie-spacers is much less than the cost of the anti-creepers.

A further advantage of my device is that by its use, it is possible to keep the ties substantially in their original position on the road bed. Since the ballast is worked under each tie to form a firm foundation, it is desirable to keep the tie on its foundation and not permit it to move forward enough to occupy what was originally the space between adjacent ties, as the ballast in this intervening space does not form as firm a foundation. The tendency of an anti-creeper, of

course, is to move the tie sidewise through the ballast. By using sufficient tie-spacers, however, this tendency is effectually resisted 45 and the initial firm foundation is made to serve its purpose indefinitely.

Of course, I do not desire to limit myself to a tie-spacer of cast metal as distinguished from one rolled or otherwise formed, particularly as the device may be made in forms somewhat different from that illustrated, and hence adapted to a rolling operation. I desire, therefore, to cover whatever suitable equivalent modifications may be devised 50 which fall within the spirit of the invention.

Having thus described my invention, what I claim as new and desire to secure by Letters Patent of the United States is:

1. A tie spacing device comprising a compression member in the form of a vertical web having lateral bearing faces at opposite ends thereof adapted to be received between the sides of adjacent ties and having a reinforcing flange arranged longitudinally 60 thereof, said flange projecting beyond the web at opposite ends to provide supporting members arranged to rest on the tops of said ties out of contact with the rail.

2. In a railway track construction, the 70 combination with a rail and a plurality of supporting cross-ties therefor, of compression members comprising vertical webs arranged in alinement at one side of but parallel to the rail, and means resting on the 75 tops of said ties and integral with said webs for supporting them.

In witness whereof, I have hereunto subscribed my name in the presence of two witnesses.

ROBERT L. COCHRANE.
